UNITED STATES PATENT OFFICE.

JOSEPH D. KILGORE, OF HOMESTEAD, PENNSYLVANIA.

TOY CANNON.

1,076,125.

Specification of Letters Patent.

Patented Oct. 21, 1913.

Application filed April 1, 1913. Serial No. 758,143.

To all whom it may concern:

Be it known that I, JOSEPH D. KILGORE, a citizen of the United States, residing at Homestead, in the county of Allegheny and 5 State of Pennsylvania, have invented new and useful Improvements in Toy Cannons, of which the following is a specification.

This invention relates to a repeating toy cannon and has for its object to provide a 10 toy of this kind which can be made strong, of relatively few and simple parts, and at a moderate expense; to provide a barrel and magazine made together of two sheets of pressed metal joined in a vertical plane 15 passing through the axes of both members; to provide a novel spring actuated discharging mechanism for the projectiles, and a novel feeding device automatically actuated by the discharging member for delivering 20 the projectiles one at a time from the magazine to the barrel.

To more clearly set forth the novel features of this invention, attention is directed to the accompanying drawings in which— 25 Figure 1 is a vertical longitudinal central section through the toy cannon and its mount, the parts being in position to discharge the projectile. Fig. 2 is a similar view of the cannon with the parts in dis- 30 charged position. Fig. 3 is a cross sectional view on the line 3—3 of Fig. 1. Fig. 4 is a perspective view of one of the pressed plates used in the construction of the barrel and magazine.

35 In the drawing wherein like reference characters are used to indicate the same parts in all the figures, 10 designates a gun carriage mounted on wheels 11 and provided with a trail 12 and upstanding arms 13 in which the cannon 14 is pivoted. The 40 cannon 14 comprises an outer casing or shell 15, preferably made in the conventional form of a cannon with trunnions 16 mounted in the arms 13 and having a knob 17, called 45 a cascabel, projecting from its rear end in which a screw bar 18 is loosely mounted by means of its enlarged head. The opposite end of the screw bar is threaded in a plate or nut 19 mounted in brackets on 50 the gun trail 12, which bar on being rotated swings the cannon on its trunnions and elevates or depresses its muzzle.

55 Within the casing or shell 15 of the cannon is placed a barrel 20 through the bore of which the projectiles 21 are discharged, said barrel having a rearward ex-

tension 22 of equal diameter and in the same axial line, connected thereto by a reduced section 23 which serves as a guide for the ejecting plunger 24. Above the 60 barrel 20 and its extension 22 is a tubular magazine 25 the forward end of which is connected to the rear end of the barrel 20 by a neck 26. The magazine 25 is placed vertically above the rear end of the barrel 65 and its extension 22, and inclines downwardly toward the barrel so that the projectiles placed therein will gravitate toward the neck 26 and into the rear end of the barrel 20. When the casing or shell 15 of 70 the cannon is in the position shown in Fig. 1, that is with its longitudinal axis horizontal, the barrel 20 is preferably at a slight upward inclination so that when projectiles are discharged therefrom they will 75 travel a greater distance than if fired in a horizontal direction. At the rear end of the magazine is an opening 27, below an opening 28 in the casing or shell 15, through which the projectiles 21 are fed into the 80 magazine, these projectiles preferably being hollow rubber balls.

Slidable longitudinally within the extension 22, in rear of the barrel 20, is the ejector plunger 24, the body of which slides freely 85 in said extension and has a forwardly projecting stem 29 guided in the reduced passage 23 between the barrel and the extension 22, and a rearwardly projecting stem 30 passing through a hole formed in the 90 headed rear end of the extension 22. Surrounding the stem 30 is a coil spring 31, pressing against the headed end of the extension and the rear end of the plunger 24, said spring tending to forcibly move the 95 plunger in a forward direction. On the underside of the body of the plunger 24 is a pin 32 which extends through a slot in the bottom of the extension 22 and into a slot in the shell or casing 15. This pin has a 100 beveled lip 33 with which engages a hook 34 on the forward end of a retracting rod 35 pivoted to a hand lever 36 fulcrumed at 37 in the gun trail 12.

Normally the ejecting plunger is in the 105 position indicated in Fig. 2 but when it is desired to discharge a projectile the hook 34 of the ejector rod is lifted into engagement with the beveled end of the pin 32 and the hand lever 36 then drawn back. This, 110 of course, retracts the plunger 24 which moves to the rear until the pin 32 has nearly

reached the limit of the slot through which it passes. This brings the retracting rod 35, just in rear of the hook 34, into engagement with a stud 38 on the underside of the shell 15, that forces the hook from the pin and releases the plunger, which, under the influence of the spring 31, is immediately carried forward and striking a projectile in the rear end of the barrel drives it out with considerable force.

10 The projectiles 21 which are fed by gravity to the barrel would, if not controlled, crowd into the barrel and interfere with the proper operation of the toy. To guard against this trouble a feeding device 40 is mounted in the neck 26, connecting the magazine to the barrel, and operated by the retraction of the plunger 24 to feed projectiles one at a time to the barrel. This feeding device comprises a cup shaped holder 41 pivoted at 42 in the neck 26, to one of which pivots is fastened an arm 43. A spring 44 attached to said arm tends to move the ejector in a forward direction while 20 a cord, chain, wire or other connection 45 extends from said arm 43 rearwardly to a pin 46, carried by the plunger 24, and slideable in a slot 47 through the top of the extension 22. When the plunger is in the discharge position, shown in Fig. 2, the feeding cup 41 is turned to the right sufficiently far to permit the lowermost projectile in the magazine rolling into said cup. Then when the plunger is retracted the connection 45, between said plunger and the feeding device, rocks the cup to the position shown in Fig. 1 whereupon the projectile contained therein falls through the neck 26 into the rear of the barrel 20. The range 25 of movement of the plunger 24 is greater than the distance moved by the arm 43 to which the connection 45 is attached. This connection therefore is made flexible so that after the cannon has been discharged and the spring 44 has turned the cup the limit of its movement to the right, said connection 30 will yield and permit the plunger to move the remaining distance without resistance or interference from said connection.

35 Attached to the underside of the reduced connection 23, between the barrel and its extension 22, is a light spring 50 the forward end 51 of which projects upward through an opening 52 in the bottom of the barrel and serves to prevent the projectiles rolling out of the muzzle should the latter be depressed. The spring, however, will readily yield when the projectile is discharged and permit the latter to pass.

40 The barrel 20, its extension 22 and the magazine 25 are formed together of two sheets of metal, cut or stamped from a flat plate, the two sheets or blanks being alike. These blanks are placed in a suitable press 45 and the portions designed for the barrel 20,

its extension 22, connecting section 23, magazine 25 and neck 26 given a semi-cylindrical shape of proper size. The forward end of the magazine is connected rigidly to the barrel by the neck 26 and to the connecting section 23 by a fin 53. Two of these stamped members are assembled by placing their edges, which lie in planes passing through the axes of the barrel and magazine, together and connecting them by a screw, rivet or 75 other fastening 54 passing through the fin 53 and a screw 55 through lugs 56 on the under side of the connecting section 23.

What is claimed is—

1. In a toy cannon, the combination of a 80 barrel, a projectile magazine and a neck connecting the barrel and magazine through which projectiles pass to the barrel, a feeding device in said neck for receiving projectiles one at a time and delivering them to the barrel, resilient means for normally holding said feeding device in position to receive a projectile, a spring actuated plunger in the barrel for ejecting the projectiles, means for retracting the plunger, means for tripping the retracting means and disengaging the plunger, and a loose connection between the plunger and the feeding device for positively actuating the latter through the movement of the former. 95

2. In a toy cannon, the combination of a 100 barrel, a projectile magazine, and a neck connecting the barrel and magazine through which projectiles pass to the barrel, made of two sheets of metal pressed into shape and joined together in a vertical plane, a feed cup pivoted in said neck for admitting projectiles one at a time to the barrel, a spring actuated plunger in the barrel for ejecting the projectiles, means for retracting the 105 plunger, means for tripping the retracting means and disengaging the plunger, and a lost motion connection between the plunger and the feeding device for automatically actuating the latter through the movement of the former. 110

3. In a toy cannon, the combination of a barrel, an extension in the rear of said barrel of like diameter, and a connecting section between the barrel and its extension of 115 less diameter to form a guide-way, a projectile magazine above the extension in the same vertical plane therewith and with the barrel and inclined thereto, a neck connecting the forward lower end of the magazine 120 to the rear of the barrel, a rocking feed cup in said neck for conveying projectiles one at a time from the magazine to the barrel, a plunger slideable in said barrel and extension provided with a forward stem to enter the 125 barrel guided in said connection section, and a rearward stem guided in a hole in the head of said extension, a coil spring surrounding the rear stem for forcing the plunger forward, retracting means for the plunger, a 130

trip for the retracting means, and a connection between the plunger and the feed cup for actuating the latter.

4. In a toy cannon the combination of a barrel, an extension on the rear of said barrel of like diameter, and a connecting section between the barrel and its extension of less diameter to form a guide-way, a projectile magazine above the extension in the same vertical plane therewith and with the barrel and inclined thereto, a neck connecting the forward lower end of the magazine with the rear of the barrel, all of said parts being formed from two sheets of metal pressed into similar halves and connected together in their central vertical plane.

5. In a toy cannon the combination of an outer casing or shell having an opening through the side at its rear end to insert

projectiles, an inner casing contained wholly 20 within said shell and separate therefrom comprising a barrel, an inclined projectile magazine, and a neck connecting the forward end of the magazine to the rear end of the barrel, said inner casing being made of 25 two like parts connected together in a plane passing through the axes of the barrel, magazine and the neck, a feeding device in said neck for delivering projectiles one at a time to said barrel, and an ejecting device 30 for driving said projectiles from the barrel.

In testimony whereof I have hereunto set my hand in presence of two subscribing witnesses.
